UNITED STATES PATENT OFFICE.

ARTHUR W. STEWART AND FRANK J. BONK, OF RIPON, WISCONSIN.

ILLUMINATED SIGN.

Application filed December 19, 1921. Serial No. 523,467.

To all whom it may concern:

Be it known that we, ARTHUR W. STEWART and FRANK J. BONK, both citizens of the United States, and residents of Ripon, 5 in the county of Fond du Lac and State of Wisconsin, have invented certain new and useful Improvements in Illuminated Signs; and we do hereby declare that the following is a full, clear, and exact description thereof.

10 Our invention relates to improvements in illuminated signs, and more particularly to a type of the same involving the use of interchangeable letters, words, or other forms of characters adapted for advertising purposes.

15 The principal object of our invention is to provide a sign or other similar form of advertising device of the character described having novel means for distributing 20 the light from a suitable illuminating medium equally to the several sign letters, words or characters.

25 Another object of our invention is to provide a sign of the character described having adjustable means for effecting the equal distribution of light to separate sections of the sign display, or to separate letters, words, characters or sections thereof and carries means for varying the length, width 30 or size of the same.

35 A further object of our invention is to provide a sign or a display device of the character described, and one of an extremely simplified construction and arrangement of parts, of low cost in manufacture, and of a wide range of utility.

40 With the foregoing and other objects in view, our invention resides in certain novel and useful construction and arrangement of parts as will be hereinafter more fully described, set forth in the appended claims, and illustrated in the accompanying drawings, in which:—

45 Figure 1 is a front elevation of a preferred embodiment of a sign having therein the adjustable light means.

Figure 2 is a longitudinal section taken on the line 2—2 of Figure 1.

50 Figure 3 is a vertical transverse section taken on the line 3—3 of Figure 1.

Figure 4 is a fragmentary detail view of one of the light adjusting elements or means, and

55 Figure 5 is a fragmentary sectional detail view taken on the line 5—5 of Figure 1.

Referring to the drawings in detail,

wherein similar characters of reference designate corresponding parts in the several views thereof, the numeral 10 indicates a sign box or housing, made of sheet metal or some suitable material and preferably rectangular in form, the same being divided longitudinally by a horizontal partition 11 to provide an upper compartment 12 and a lower compartment 13, the open front sides of both compartments being each provided with closure frames 14 and 15, the frame 14 being hinged as at 16, to the front edge of the partition 11 for a vertical swinging movement, and the frame 15 hinged as at 17, to the front edge of the bottom wall of the lower compartment.

The inner edges of the side and end bars or rails forming the open frames 14 and 15 are grooved, as at 18 and 19 respectively, from the inner sides of the frames for the reception of transparent closures or panes of glass 20 and 21, and for interchangeable sign plates or sheets 22 and 23 upon which are arranged any suitable advertising matter desired. These signs or plates 22 and 23 are preferably transparent for instance of celluloid, for the illuminating of the same from sets of electric lamps 24 and 25 located in equidistantly spaced relation within the compartments 12 and 13, respectively. The sign plates or sheets 22 and 23 are further mounted in frames 26 and 27, respectively, which are to be removably fitted into the grooves 18 and 19 of the closure frames 14 and 15 in rear of the glass panes 20 and 21, the frames being swung to open position for such purpose.

The frames 14 and 15 are held in normally closed position by means of a spring tensioned detent 28 carried in the underfaces of the top wall of the upper compartment and in the partition wall 11 forming the top of the lower compartment 13, and which are adapted to engage and disengage complementary recesses formed in the top edges of each of the frames 14 and 15.

Hinged to the rear wall of each compartment, as indicated at 29 and 30, are a series of partitions 31 and 32, preferably formed of sheet metal, one disposed medially between adjacent pairs of lamps 24 and 25, respectively, and the same are of an area slightly less than the cross-sectional area of the compartments 14 and 15. Mounted on each of the partitions 31 and 32 are adjustable partition plates 33 and 34, respectively,

the same comprising metal plates having their upper and lower edges folded, as at 35 and 36, to provide channel ways in sliding engagement with the upper and lower 5 edges of the partitions 31 and 32.

In the use of the device or sign, sign plates are positioned within the frames 14 and 15, as hereinbefore explained, and the partitions 31 and 32 are swung to positions corresponding to the division lines or spaces between the letters, words or characters arranged on the sign plates, so that, when the frames are closed, the light from the lamps 24 and 25 will be directed through the proper section 10 or compartment of the sign plates, the adjustable partition plates 33 and 34 being adjusted on the hinged plates 31 and 32 correspondingly for the angular disposition of the latter with respect to their normal transverse positions, and in a manner to completely close one compartment section from the other.

It is well understood that while the device or sign has been described and illustrated herein in specific terms and details of construction and arrangement, various changes in and modifications thereof may be resorted to without departing from the spirit of the invention, or scope of the claims appended hereto.

Having thus fully described our invention, what we claim as new, and desire to secure by Letters Patent is:—

1. A sign box having an open side, interchangeable transparent plates adapted to

close said open side, lamps equidistantly spaced within said box, partitions hingedly connected to the rear wall of said box and adapted to be adjusted transversely of the said box, and said partitions adapted to be 40 adjusted to a length greater than the width of said box for directing the light from said lamps to portions of said sign plates.

2. In a sign, a housing having an open front side, interchangeable transparent sign 45 plates adapted to close said open side, lights spaced equidistantly within said housing, and movable partitions arranged between each of said lamps and adjustable to direct the light from said lamps to complementary 50 portions of said sign plate and correspondingly for portions of the latter of varying sizes.

3. In a sign, a housing having an open front side, interchangeable transparent sign 55 plates adapted to close said open side, lamps equally spaced within said housing, and extensible transversely disposed partitions hingedly mounted within said housing and between said lamps and movable to direct 60 the light from said lamps to complementary portions of said sign plate and correspondingly for portions of the latter of varying sizes.

In testimony that we claim the foregoing 65 we have hereunto set our hands at Ripon, in the county of Fond du Lac and State of Wisconsin.

ARTHUR W. STEWART.
FRANK J. BONK.
